HARVEY JOHN GEHR, OF WAYNESBORO, PENNSYLVANIA.

DEVICE FOR BALANCING DRUMS, &c.

1,279,322.

Specification of Letters Patent. Patented Sept. 17, 1918.

Application filed November 22, 1917. Serial No. 203,388.

To all whom it may concern:

Be it known that I, HARVEY JOHN GEHR, a citizen of the United States, residing at Waynesboro, in the county of Franklin and

5 State of Pennsylvania, have invented a new and useful Device for Balancing Drums, &c., of which the following is a specification.

This invention has reference to devices for balancing machine elements such as drums 10 and the like, whereby the drums may be quickly and accurately balanced to prevent undue strain upon the parts carrying them, especially when the drums are driven at high speed.

15 In accordance with the invention, there is provided an upright shaft capable of being driven at high speed. At the upper end of the shaft there is provided a loose sleeve closed at one end and supported by the shaft in such manner that the sleeve is pendulously carried with a capability of swing of very limited extent. The sleeve is arranged so as to carry the drum to be balanced, and associated with the drum is

25 a marker so constructed that with what constitutes the upper surface of the drum rotating at relatively slow speed, the position of the marker may be ascertained, and then by highly increasing the speed of the drum 30 another reading of the marker may be taken showing any oscillation of the drum about its axis of rotation. Should oscillation occur, the marker may be made to produce an indication on the drum at the high side

35 thereof, and a reading may be taken of the position of the marker at such time so that not only is the high side of the drum indicated, but the amount of oscillation is measured. By such means, an operator is guided

40 in adjusting the balance of the drum until such drum will rotate at high speed without oscillation.

The invention will be best understood from a consideration of the following detailed description, taken in connection with the accompanying drawings forming part of this specification, with the further understanding that, while the drawings show a practical form of the invention, the latter 45 is not confined to any strict conformity with the showing of the drawings but may be changed and modified so long as such

changes and modifications come within the scope of the appended claims.

In the drawings:

Figure 1 is an elevation of an embodiment of the invention showing a drum in place;

Fig. 2 is a longitudinal diametric section of a portion of the drum-carrying shaft and 60 of the shaft-carried sleeve on which the drum is secured;

Fig. 3 is a section of the sleeve on the line 3—3 of Fig. 2, the shaft and key being shown in plan;

Fig. 4 is a top plan view of the shaft.

Referring to the drawings, there is shown a shaft 1 mounted in bearings 2 upon supports 3. The shaft, in operation, is upright and is adjusted as carefully as may be to 70 rotate about a vertical axis. A collar 4 resting on the lower bearing 2 serves to support the shaft, although any kind of a step bearing suitable for the purpose may be employed. The shaft carries a pulley 5 forming a convenient means for the application of a belt to drive the shaft. The pulley 5 is to be taken as indicative of any suitable means for driving the shaft.

Since, in operation, the shaft is upright, 80 terms of position as hereinafter used will have reference to the working position of the shaft.

The upper end 6 of the shaft is rounded or approximately semi-spherical, and has a 85 diametric groove 7 formed at its apex.

Mounted on the upper end of the shaft 1 is a sleeve 8 having an axially extended chamber 9 terminating near the top of the sleeve in a rounded end wall 10 of approximately semi-spherical shape and described on a longer radius than the end 6 of the shaft. Above the chamber 9 the sleeve 8 has a solid extension 11.

The sleeve 8 has an external diameter to 95 snugly fit the bore of a drum 12 to be balanced, said drum having the usual hubs 13 through which are tapped set screws 14 utilized for fastening the drum securely to the sleeve 8. A set collar 15 held to the 100 sleeve 8 by a set screw 16 serves as a support for the drum determining the height of its position on the sleeve 8 before the set screws 14 are screwed home.

2
 The sleeve 8 is constrained to rotate with the shaft 1 by a pin or key 17 traversing the sleeve in such position that one portion of it is seated in the solid member 11 of the 5 sleeve 8 and another portion enters the groove 7. The pin or key 17 forms a connection between the shaft and the sleeve, but need not seat to the bottom of the groove, and does not tightly fit the groove 10 so that there is opportunity for the sleeve 8 to rock on the shaft, such rocking being facilitated by the convex end of the shaft seating in the concave end of the chamber 9 after the manner of a somewhat loose universal joint.

Pivoted at one end to a convenient support 18 is an arm 19 overlying the shaft 1 and at the end remote from the support 18 provided with a handle 20. The arm 19 moves over a scale 21 and may be provided with a slot 22 through which the scale is readable. Of course, any other arrangement whereby the relation of the arm to the scale is made evident may be employed. 25 Mounted on the arm 19 is a marking implement 23, such, for instance, as a pencil, so arranged that the marking end of the pencil may be brought into contact with the upper end of the surface of the drum 12, the arm 30 19 with the pencil 23 being under the control of an operator.

The drum 12 having been properly finished, especially with respect to what constitutes its upper surface when on the shaft 35 1, to rotate in a horizontal plane when the shaft 1 is upright or plumb, and with the lower hub 13 resting on the collar 15 and the key or pin 17 engaging in the groove 7, the drum may be considered as in a state of 40 equilibrium. Under these conditions, the drum and the sleeve 11 are pendantly supported by the shaft 1, the drum being so seated on the sleeve that the location of the upper end of the shaft with respect to the 45 concave end of the chamber 9 of the sleeve 11 is above the center of the drum. Now, by rotating the shaft 1 slowly and bringing the pencil 23 into light contact with the upper surface of the drum, a mark will be produced on the drum entirely around the upper surface of the drum, care being taken to 50 avoid such pressure as would throw the drum out of adjustment. Note is taken of the position of the arm 19 on the scale 21, 55 and then the drum is rotated at a very high rate of speed, the pencil 23 having in the meantime been moved out of contact with the drum. Now, if there be inaccuracies of balance in the drum, it will no longer remain 60 truly horizontal, but will rock or swing. Then if the pencil 23 be again brought into light contact with the drum, which contact can be very delicately ascertained by "feel," and note be taken of the position of the arm 65 19 with respect to the scale 21, the mark

produced by the pencil will extend through a small arc on the face of the drum. This indicates at what point the drum is out of balance, while the difference in the reading of the scale will indicate the degree of out 70 of balance. The machine is then stopped, the drum is removed and rebalanced, and the operation is repeated if necessary until the drum is put in running balance.

The structure of the invention is one of 75 great delicacy with respect to the putting of the drum into running balance, and is intended to be used where a high degree of refinement is essential. More pronounced inaccuracies of balance may be ascertained 80 by other and simpler means, but such means do not indicate the small inaccuracies in balance which are multiplied and become more pronounced when the drum is rotated at high speed.

85 The utilization of the sense of touch is of importance, and this permits the touching of the pencil to the high side of the drum when out of balance and tilted by the high speed of rotation, since the pencil may be 90 made to touch the drum so gently that equilibrium will not be disturbed, for otherwise the mark recorded on the drum would not truthfully indicate the location of the inaccuracy in balance.

95 While the invention is not limited to the balancing of drums, the term "drum" is used in the claims for simplicity of expression and is to be interpreted as broad enough in scope to cover any structure to be put 100 into running balance, for which structure the device of the invention is adapted.

What is claimed is:

1. A device for balancing drums comprising an upright rotatable shaft, a sleeve 105 loosely supported by and rotatable with the shaft and capable of rocking with respect to the axis of rotation of the shaft, said sleeve being of a size to receive and hold a drum, and marking and indicating means for locating the part of the drum out of balance and the degree thereof.

2. A device for determining the degree of out of balance in drums preparatory to balancing the drums, comprising an upright 115 rotatable spindle, a support for a drum loosely carried by the spindle and provided with means for locating a drum on the spindle, with the point of support of the sleeve higher than the midpoint of the 120 drum and sleeve combined when the latter is rotating on an upright axis, and means associated with the spindle and sleeve for indicating the amount of tilt of the drum when out of balance and rotating at high 125 speed, and also the high point of the tilted rotating drum.

3. A device for determining the degree of out of balance in drums preparatory to balancing the drums, comprising an upright ro- 130

tatable shaft or spindle, an upright sleeve pendulously carried by the spindle for receiving and supporting the drum to be balanced, and hand operated means for marking the drum and indicating the degree of out of balance.

4. A device for determining the degree of out of balance in drums preparatory to balancing the drums, comprising a rotatable upright shaft or spindle having a convex upper end with a transverse groove therein, a sleeve closed at the upper end and having an interior diameter greater than the diameter of the spindle to permit the sleeve to rock on the spindle, said sleeve having an interior concave wall at the closed end, a connecting pin loosely fitting the transverse groove in the upper end of the shaft or spindle, and marking means for hand operation associated with the shaft or spindle and sleeve carried thereby to mark a drum mounted on the sleeve and rotated thereby and to indicate the degree of out of balance of the drum.

5. A device for determining the degree of out of balance in drums preparatory to balancing the drums, comprising a rotatable upright shaft or spindle having a convex

upper end with a transverse groove therein, a sleeve closed at the upper end and having an interior diameter greater than the diameter of the spindle to permit the sleeve to rock on the spindle, said sleeve having an interior concave wall at the closed end, a connecting pin loosely fitting the transverse groove in the upper end of the shaft or spindle, and marking means for hand operation associated with the shaft or spindle and sleeve carried thereby to mark a drum mounted on the sleeve and rotated thereby and to indicate the degree of out of balance of the drum, said hand operated marking means comprising an arm pivotally supported at one end and arranged to be grasped by the hand at the other end, a scale associated with the arm, and means for holding a marking implement in position to contact with the drum while being rotated.

In testimony that I claim the foregoing as my own I have hereto affixed my signature in the presence of two witnesses.

HARVEY JOHN GEHR.
